CLAIM

The ornamental design for a holder for roller paper cutter, as shown and described.

DESCRIPTION

FIG. 1 is a perspective view of a holder for roller paper cutter showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged view of FIG. 4; and,

FIG. 9 is an enlarged view of FIG. 5.

The broken lines immediately adjacent to the shaded areas depict the bounds of the claimed design, while all other

(Continued)

broken lines are directed to environment. The broken lines form no part of the claimed design.

1 Claim, 9 Drawing Sheets
